Primary Examiner—Caron D. Veynar*Assistant Examiner*—Ricky Pham(74) *Attorney, Agent, or Firm*—MacMillan, Sobanski & Todd, LLC(57) **CLAIM**

The ornamental design for a handle for a utensil, as shown and described.

DESCRIPTION

FIG. 1 is a top plan view of a handle for a utensil according to the design;

FIG. 2 is a right side elevational view thereof;

FIG. 3 is a bottom plan view thereof;

FIG. 4 is a left side elevational view thereof;

FIG. 5 is a first end elevational view thereof;

FIG. 6 is a second end elevational view thereof; and,

FIG. 7 is a cross-sectional view taken along line 7—7 of FIG. 1.

The broken lines shown in FIGS. 1–4 are illustrative of environmental structure only and form no part of the claimed design.
